MEANS FOR COLLECTING EMPTY BOBBINS

William C. Gibson, Jr., Atlanta, Ga.

Application January 2, 1948, Serial No. 210

12 Claims. (Cl. 57—1)

1

My invention relates to means for collecting empty bobbins as used on spinning machines, as the yarn or thread thereon is used up and the bobbins are replaced by fresh bobbins on which the yarn is wound.

It is the custom in spinning mills for the operators of the spinning frames to replace the empty bobbins on the top of the frame or creel board thereof, which is usually a flat surface. Thereafter, the empty bobbins are manually collected. Such method and manner of disposing of the empty bobbins is objectionable, since the empty bobbins on top of the frame or creel board have a tendency to fall off on account of vibration, and sometimes injure the worker, or damage the machine and material by rolling under the frame and interfering with the necessary movement of the machine parts. Moreover, collection of empty bobbins from along the entire length of the frame requires the services of numerous personnel and is unduly laborious and expensive.

With the foregoing in view, it is an object of my invention to provide improved means for collecting empty bobbins from a spinning frame.

A further object is to provide improved means for collecting empty bobbins from along the entire length of a spinning frame, which includes the provision of a trough on each side of the frame and extending the entire length thereof, said trough being adapted to receive a single row comprising a plurality of empty bobbins in end-to-end relation, whereby the end bobbins of the row may be discharged from the ends of the trough as the row is pushed along the trough.

A further object of the invention is to provide in a device such as that last described at least one receptacle carried by said frame in subjacent relation to said troughs, whereby to receive bobbins discharged from said troughs.

A further object of the invention is to provide in a device such as that last described means hingedly mounting said receptacles on said frame, whereby the same may be readily swung from an operative bobbin-receiving position to a discharge or bobbin-dumping position.

Other objects and advantages reside in the particular structure of the invention, combination and arrangement of the several parts thereof, and will be readily understood by those skilled in the art upon reference to the attached drawings in connection with the following specification, wherein the invention is shown, described and claimed.

In the drawings:

Figure 1 is a fragmentary side elevation of a spinning machine or frame showing the empty bobbin-collecting means in position thereon;

Figure 2 is a top plan view of the structure shown in Figure 1;

2

Figure 3 is an end elevation looking toward the right in Figures 1 and 2;

Figure 4 is a longitudinal vertical sectional view taken substantially on the plane of the line 4—4 of Figure 3.

Figure 5 is an enlarged transverse vertical sectional view on an enlarged scale and taken substantially on the plane of the line 5—5 of Figure 1;

Figure 6 is a perspective view of a supporting bracket for the trough.

Referring to the drawings in detail, in which like reference characters designate corresponding parts throughout the several views, there is shown in Figures 1 and 2 a spinning machine or frame 10 having the usual step supports 11 and 12, head ends 13 and creel boards 14 at the top provided with the usual side flanges 15. The bobbins are indicated at 16, bearing the yarn 17, fed therefrom during the operation of the machine in the ordinary spinning operation, the details of which may vary with different types and lay-outs of spinning machines or frames. The ends 13 of the frame may be supported upon a suitable base 18 anchored to the floor in the usual manner.

In accordance with the present invention, troughs 19 are supported in a suitable position along the longitudinal side edges of the top or creel board 14 so as to project laterally outwardly therefrom on either side thereof. These troughs 30 run longitudinally of the frame the full length thereof, and may be supported or secured in position in any suitable manner, as by means of brackets or straps 20 suitably secured, as indicated at 21, by means of screws or the like, to the bottom of the spinning frame top or creel board 14. The brackets 20 may have their ends bent into depressed, arcuate or semi-circular trough-receiving and supporting portions 22 retaining the trough 19 therein outwardly of the sides of the creel board 14 and flanges 15 thereof. The brackets 20 are provided with suitable openings or holes 23 for receiving the fastening means 21, or may be otherwise suitably secured in position, and may be provided with suitable means, such as the holes 24, in their curved portions 22 to provide means for securing the same to the troughs, as indicated at 25, so that the troughs will be securely retained in position. One end of each trough may be closed, as indicated at 26 (Figure 5), while the opposite end is open and projects over the vertical or head end portion 13 of the spinning frame, as indicated at 27 in Figures 1, 2 and 4 of the drawings.

A receptacle 28 of any suitable form is located 55 on the frame 10 under each open end 27 of the troughs 19 to receive successively the end bobbins B of a row of bobbins placed in the troughs by the operators. In this connection, it should be noted that the troughs 19 are sized so that 60 they can contain but a single row comprising a

plurality of bobbins in end-to-end relation. Thus, as a bobbin is added to a trough, the operator pushes the row along to make room for it, whereby to push the end bobbins from the discharge end of the trough when the trough is full. The receptacle or box 28 receives the bobbins as they are discharged from the troughs. This receptacle may be of any suitable shape, but is preferably elongated transversely and rectangular in plan with an inclined open top 29 extending under both troughs at its low inner end wall and constituting at its high outer end wall means to prevent the bobbins from escaping over the receptacle as they are discharged thereinto from the trough. The bottom of the receptacle in the embodiment shown has a raised or offset portion 30 fitting over an offset raised portion 31 of the particular head end of the frame shown, and is hinged so as to be tilted outwardly for emptying the empty bobbins therefrom for collection. The receptacle is also mounted for lateral movement in either direction in a horizontal plane to permit necessary inspection, oiling and repairs of parts of the machine covered thereby. This may be accomplished in any suitable manner, and by any suitable construction, as will appear later. The receptacle 28 is slightly wider than the creel board 14 so as to project outwardly thereof at each side beyond the troughs 10. Thus, the discharge ends 27 of the troughs are disposed over the receptacle as it rests upon the end 13 of the frame at the top thereof. Obviously, the receptacle may assume other forms to conform to the structure of the particular frame with which it is to be used.

Hinge members comprising bars or brackets 32 are extended horizontally of and are secured to the top of the head end 13 of the frame, as indicated at 33. These hinge brackets may be of angular form and may have right-angled vertical legs 34 substantially flush with the vertical edge or end of the end frame 13. The free ends of legs 34 may be curled or looped, as indicated at 35, to a hinge rod or pintle 36 extending transversely of the outer vertical wall of the receptacle and carried by end plates 37 attached to the sides of the receptacle, preferably slightly below the center of the receptacle or at the lower part thereof. With the pintle recessed or set in a transverse groove 40 of the outer wall of the receptacle, as shown, the receptacle may tilt outwardly on the loops 35 to discharge empty bobbins. Also, since the receptacle is loosely hinged to the pivot brackets 32, one or two of which are employed in inwardly-spaced relation to the end plates 37 thereof, the receptacle is free to move or slide in a horizontal plane laterally in either direction, as indicated in broken lines in Figure 2 of the drawings. This movement will expose the end of the machine and permit necessary inspection, oiling and repair of covered parts.

Of course, the dimensions and design of the receptacle and troughs may be varied for different types or sizes of machines or spinning frames, and the pivoted or hinged mounting of the receptacle may be varied to conform to different types and lay-outs of different installations. In like manner, the troughs may be formed to provide integral parts of the creel board and may be positioned otherwise than as shown. The basic idea is to mount or form the receptacle to facilitate the removal of the contents thereof when the receptacles are emptied to form or position the troughs for convenient use.

While I have shown and described what is now

thought to be a preferred embodiment of the invention, it is obvious that the same is susceptible of other forms and expressions. Consequently, I do not limit myself to the precise structure shown and described, except as hereinafter claimed.

I claim:

1. The combination with an elongated spinning frame, of means for collecting empty bobbins from said frame, said means comprising a pair of troughs, means mounting one of said troughs along each side of said frame, said troughs being adapted to receive empty bobbins therein, at least one receptacle for said empty bobbins, and means mounting said receptacle at one end of said frame to receive said empty bobbins from said troughs.

2. The combination with an elongated spinning frame, of means for collecting empty bobbins from said frame, said means comprising a pair of troughs, means mounting one of said troughs along each side of said frame, said troughs being adapted to receive empty bobbins therein, at least one receptacle for said empty bobbins, means mounting said receptacle across one end of said frame in subjacent relation to both of said troughs, and said last-named means including a pivotal connection with said receptacle whereby the latter may be tilted to empty the same.

3. The combination with an elongated spinning frame, of means for collecting empty bobbins from said frame, said means comprising a pair of troughs, means mounting one of said troughs along each side of said frame, said troughs being adapted to receive empty bobbins therein, at least one receptacle for said empty bobbins, said receptacle extending transversely across one end of said frame in subjacent relation to both of said troughs to receive said empty bobbins therefrom, hinge means hingedly connecting said receptacle to said frame to permit swinging of said receptacle relative to said frame to and from bobbin-receiving and bobbin-dumping positions, and said hinge means including means slidably mounting said receptacle for lateral sliding movement relative to said frame.

4. The combination with a spinning frame having sides, ends and a top creel board; of a pair of longitudinally-extending troughs, one of said troughs being associated with each side of said creel board and extending longitudinally substantially the entire length thereof, said troughs each having a laterally-aligned discharge end at least one end of said frame, a receptacle, means pivotally mounting said receptacle on said frame at said end thereof in subjacent relation to said discharge ends of said troughs, each trough being sized to receive a single row of empty bobbins in end-to-end relation and to discharge the end bobbins into said receptacle as said row is pushed along said trough, and said receptacle being adapted to be tilted upon said last-named means for discharging empty bobbins collected therein therefrom.

5. The combination with an elongated spinning frame having an elongated top creel board above the same, of a trough secured along each side edge of said board, said troughs having laterally-aligned closed ends at one end of said board and open discharge ends at the other end of said board, said troughs being each adapted to receive a single row comprising a plurality of empty bobbins in end-to-end relation, each row being adapted to be pushed along its trough to

successively discharge end bobbins from said open end, said machine having an end frame member, a receptacle, and means mounting said receptacle on said end frame member in subjacent relation to said discharge open ends of said troughs to receive said empty bobbins discharged therefrom.

6. The combination with an elongated spinning frame having an elongated top creel board above the same, of a trough secured along each side edge of said board, said troughs having laterally-aligned closed ends at one end of said board and open discharge ends at the other end of said board, said troughs being each adapted to receive a single row comprising a plurality of empty bobbins in end-to-end relation, each row being adapted to be pushed along its troughs to successively discharge end bobbins from said open ends, said machine having an end frame member, a receptacle, means mounting said receptacle on said end frame member in subjacent relation to said open ends of said troughs whereby to position said receptacle to receive said empty bobbins discharged from said troughs, and said last-named means mounting said receptacle for lateral sliding and vertical swinging movement on said frame.

7. The combination with an elongated spinning frame having an elongated top creel board above the same, of a trough secured along each side edge of said board, said troughs having laterally-aligned closed ends at one end of said board and open discharge ends at the other end of said board, said troughs being each adapted to receive a single row comprising a plurality of empty bobbins in end-to-end relation, each row being adapted to be pushed along its trough to successively discharge end bobbins from said open end, said machine having an end frame member, a receptacle, means mounting said receptacle on said end frame member in subjacent relation to said open ends of said troughs whereby to position said receptacle to receive said empty bobbins discharged from said troughs, said receptacle having front and rear end walls, said rear end wall being formed to provide a transverse groove therein, means mounting a pivot pin in said groove, at least one hinge member, means rigidly mounting said hinge member on said frame in subjacent relation to said receptacle, said hinge member having a free end formed to provide a loop, and said loop being slidably and pivotally engaged with said pivot pin, whereby to mount said receptacle on said frame for vertical swinging movement and lateral sliding movement relative thereto.

8. The combination with an elongated spinning frame having an elongated top creel board above the same, of a trough secured along each side edge of said board, said troughs having laterally-aligned closed ends at one end of said board and open discharge ends at the other end of said board, said troughs being each adapted to receive a single row comprising a plurality of empty bobbins in end-to-end relation, each row being adapted to be pushed along its trough to successively discharge end bobbins from said open end, said machine having an end frame member, a receptacle, means mounting said receptacle on said end frame member in subjacent relation to said open ends of said troughs whereby to position said receptacle to receive said empty bobbins discharged from said troughs, said receptacle having front and rear end walls, said rear end wall being formed to provide a transverse groove

therein, means mounting a pivot pin in said groove, at least one hinge member, means rigidly mounting said hinge member on said frame in subjacent relation to said receptacle, said hinge member having a free end formed to provide a loop, said loop being slidably and pivotally engaged with said pivot pin, whereby to mount said receptacle on said frame for vertical swinging movement and lateral sliding movement relative thereto, means mounting said troughs on said board, said last-named means comprising a plurality of longitudinally-spaced transversely-extending hanger members, means rigidly mounting said hanger members to the under side of said board, said hanger members including free ends extending laterally outwardly of said board, and means rigidly connecting said free ends to said troughs to support the latter.

9. The combination with a spinning frame having sides and ends; of means providing a pair of longitudinally-extending troughs, one of said troughs being associated with each side of said frame and extending longitudinally substantially the entire length thereof, said troughs each being formed with at least one open discharge end at at least one end of said frame, each trough being adapted to receive therein at least one row comprising a plurality of empty bobbins in end-to-end relation and to discharge successively the end bobbins of said row through said open end as said row is manually pushed along said trough.

10. The combination with a spinning frame having sides, ends and a top creel board; of means providing a pair of longitudinally-extending troughs, one of said troughs being associated with each side of said creel board and extending longitudinally substantially the entire length thereof, said troughs each being formed with at least one open discharge end at at least one end of said creel board, each trough being adapted to receive therein at least one row comprising a plurality of empty bobbins in end-to-end relation and to discharge successively the end bobbins of said row through said open end as said row is manually pushed along said trough.

11. The combination with a spinning frame having sides and ends; of a pair of longitudinally-extending troughs each being substantially co-extensive in length with said creel board, means mounting one of said troughs along each side of said creel board, said troughs each being formed with at least one open discharge end at at least one end of said frame, each trough being adapted to receive therein at least one row comprising a plurality of empty bobbins in end-to-end relation and to discharge successively the end bobbins of said row through said open end as said row is manually pushed along said trough.

12. The combination with a spinning frame having sides, ends of a top creel board; of means providing at least one longitudinally-extending trough, said trough being associated with said creel board and extending substantially the entire length thereof, said trough being formed with at least one discharge opening at at least one end of said creel board, said trough being adapted to receive therein at least one row comprising a plurality of empty bobbins in end-to-end relation, and said row of bobbins being adapted to be pushed manually along said trough toward said discharge opening whereby to discharge successively the end bobbins through said discharge opening.

WILLIAM C. GIBSON, JR.
